UNITED STATES PATENT OFFICE.

CHANCY K. MILTIMORE, OF JANESEVILLE, WISCONSIN.

POCKET PROTECTOR.

1,409,306.

Specification of Letters Patent. Patented Mar. 14, 1922.

Application filed March 22, 1919. Serial No. 284,250.

To all whom it may concern:

Be it known that I, CHANCY K. MILTIMORE, a citizen of the United States, and a resident of the city of Janesville, county 5 of Rock, and State of Wisconsin, have invented certain new and useful Improvements in Pocket Protectors, of which the following is a specification.

My invention relates to a pocket protector, and has for its object the production of a device which will prevent the contents of a pocket in clothes from slipping out or being easily removed while the same is being worn.

15 Other objects will appear hereinafter.

The invention consists in the combinations and arrangements of parts herein-after described and claimed.

The invention will be best understood 20 by reference to the accompanying drawings forming a part of this specification, and in which,

Fig. 1, represents a perspective view of the device in modified form,

25 Fig. 2, is a side elevation of the device applied, partly in section;

Fig. 3, is a perspective view of the device, and

Fig. 4, represents a side elevation of Fig. 30 3, showing the device applied.

The preferred form of construction, as 35 illustrated in the drawings, comprises a main body 1, formed preferably of metallic steel, having one end doubled upon itself as at 2, forming a clamp thereby. The lower end of member 1 is inwardly turned, as at 4, for the purpose of affording a closer contact between said member 1 and the article held thereby. The doubled-over 40 portion 2, at its lowest extremity, is outwardly offset as at 3, for the purpose of permitting the object to be clamped thereby to slide more readily between the doubled-over portion and the elongated 45 portion of member 1. In Fig. 2, the device is shown in its applied position, 5 representing the pocket, and 6, a pocket-book or contents of the pocket. The device is used to protect the contents of a 50 pocket and is applied by sliding the doubled-over portion 2 on the inside of the belt or waist-band 10 of a pair of trousers, thereby securely clamping the belt or waist-band. The lower end of member 1 55 is then inserted in the hip pocket 5 of the

trousers, so as to press the pocket-book or other contents 6 of the pocket closely against the body of the person. When this device is thus applied, removal of the contents of the pocket therefrom becomes difficult, and impossible without ordinarily attracting the attention of the wearer.

60 A modified form of the device is shown in Figs. 3 and 4, in which a lip 7 is punched out of the member 1 and buckled to form a groove 8 for the reception of a key ring 9. In this modified form the device serves the purpose of also providing a key ring carrier.

65 While I have illustrated and described the preferred form of construction for carrying my invention into effect, this is capable of variation and modification without departing from the spirit of the invention. I, therefore, do not wish to be limited 70 to the precise details of construction set forth, but desire to avail myself of such variations and modifications as come within the scope of the appended claims.

75 Having described my invention, what I claim as new and desire to secure by Letters Patent is:—

1. A pocket-protecting device comprising a main body having one end doubled upon itself to form a clamp, the lower end 80 of said body being adapted to be inserted in a pocket to press the contents thereof against the body of the wearer; an integral lip formed at the upper end of said body, said lip being buckled to form a groove; and a key ring inserted in said groove, substantially as described.

85 2. A pocket-protecting device comprising a body having one end doubled upon itself to form a clamp, said clamp arranged to receive a belt and support the said body in a pocket, the lower portion of said body arranged to press the contents thereof against the body of the wearer; an integral lip formed at the upper end of said body, 90 said lip being buckled to form a groove; and a key ring inserted in said groove, substantially as described.

95 In testimony whereof I have signed my name to this specification in the presence 100 of two subscribing witnesses.

CHANCY K. MILTIMORE.
